WEFT TENSION TAKE-UP FOR LOOMS

Hardy Bruce Gosnell, Slater, S. C.

Application December 15, 1947, Serial No. 791,788

6 Claims. (Cl. 139—194)

1

This invention relates to looms and more especially to a device for holding tension in the weft or filling yarns between the edge of the fabric and the shuttle box as the shuttle is in the box and as it is being forced out of the shuttle box with the object of avoiding kinks or loops in the filling being left in the cloth.

The principal object of the invention is to provide a device which may be used with equally good results to insure the tension in the filling being properly held until bound in the cloth by the changing of the shed or beat up of the lay of the loom whether the filling be strong or exceedingly weak.

Some of the objects of the invention having been stated, other objects will appear as the description proceeds, when taken in connection with the accompanying drawings, in which

Figure 1 is a top plan view of the loom showing one form of my invention near each end of the lay of the loom;

Figure 2 is a fragmentary isometric view showing my invention near the left-hand end of the lay;

Figure 3 is an elevation with parts in section showing the lay in the foremost or beat-up position and being taken substantially along the line 3—3 in Figure 1;

Figure 4 is a view similar to Figure 3 but showing the parts in a different position;

Figure 5 is a top plan view of a loom and is similar to Figure 1 but showing a modified form of the invention applied to opposed ends of the lay;

Figure 6 is a vertical sectional view taken substantially along the line 6—6 in Figure 5 and showing the modified form of the invention applied near the right-hand end of the lay with the lay in beat-up position;

Figure 7 is a vertical sectional view similar to Figure 6 but showing the parts in a different position;

Figure 8 is an isometric view of the modified form of the invention as it appears when applied to the right-hand end of the lay of the loom.

Referring more specifically to the drawings, the numeral 10 indicates the left-hand vertical side frame member of a loom and the numeral 11 indicates the right-hand vertical side frame member of the loom. Secured between the vertical side members 10 and 11 is a breast beam 14 by means of a bolt 18. The plate 17 is a part of a conventional magazine, not shown. Another

2

plate 19 connects the breast beam 14 to the side frame 10 in a conventional manner. Disposed between the vertical side frame members 10 and 11 are vertically disposed swords 12 and 13 which are oscillatably mounted on a rocker shaft, not shown, and have oscillatably mounted near their upper ends and on stub shafts 20 and 21 respectively the forward ends of pitman rods 15 and 16 respectively.

10 A conventional lay 23 is secured to the swords 12 and 13 by means of bolts 24 and 25, respectively, and the lay 23 has secured thereto a conventional race plate 26. The lay 23 extends beyond the frame members 10 and 11 at each end 15 and has integral therewith conventional shuttle boxes 28 and 29 which consist primarily of a front box plate 30 and a binder 31.

By referring to Figure 1 there may be observed in the left-hand shuttle box 28 a shuttle 35 in 20 which is disposed a bobbin 36 and the end of the shuttle 35 is engaged by a picker stick 37, a similar picker stick 38 being shown in the shuttle box 29.

The lay 23 and the race plate 26 having coinciding cut out portions 39 and 40 therein normally used in which a grate for a filling feeler apparatus is but which is not employed in the operation of this mechanism and is thus omitted.

Secured to the upper ends of the swords 12 30 and 13 respectively by means of bolts 45 and 46 are angle clips 47 and 48 which extend forwardly as at 49 and 50 and have secured therebetween a reed cap 52 by means of bolts 53 and 54 respectively. Clamped between the reed cap 52 35 and the lay 23 is a vertically disposed reed 56 which has passing therethrough a plurality of warp yarns 57 which extend forwardly and merge with a cloth portion 58. The parts which have heretofore been described are the principal 40 conventional parts of a loom with which my invention is associated and the following parts are those comprising my invention.

Since the parts of the present invention as applied to the left-hand end of the lay 23 in Figure 1 are identical to the parts at the right-hand end thereof, except being opposite hand, only the parts at the left-hand end of the lay 23 will be described and like parts at the right-hand end of the lay will bear like reference characters with the prime notation added.

The vertical side frame member 10 extends upwardly as at 60 (Figure 4) and has secured to a webbed portion 61 thereof a bolt 65 which secures on one side thereof by clamping, a horizontally disposed cam member or bar 66.

The horizontally disposed bar 66 is rectangular in cross section and extends forwardly (Figure 4) and then downwardly and again forwardly and is engaged by a grooved follower wheel 70. The follower wheel 70 is rotatably mounted on a transverse portion 71 and is confined by a nut 72 which is threadably mounted on the end of the portion 71. Adjacent the follower wheel 70 is one end of a tension spring 75 which, at its upper end, is secured to the portion 71 and extends downwardly and forwardly and is secured to the binder 31 at its lower end by means of a screw 76.

The portion 71 is bent at right angles to form a portion 74 which projects forwardly and downwardly as viewed in Figure 1 and is bent transversely to form a portion 78 which is oscillatably mounted in bearings 80 which are secured, by any suitable means such as spot welding, to a horizontal portion 81 of an angle bracket having an upturned portion 82 which is secured to the vertical surface of the angle clip 47 by any suitable means such as a screw 85. It is manifest that the upturned portion 22' of the angle bracket is secured by screw 85' to the angle clip 48.

The horizontal portion 78 of the shaft 71 extends through the bearings 80, and to the right as observed in Figures 1 and 2 and, as may be observed, has threadably mounted thereon a nut 87. Adjacent the nut 87 is a downwardly projecting finger 89 which is secured on the shaft 78 by another nut 90 which is threadably secured on the shaft 78. It is thus seen that the finger 89 may be adjusted between the nuts 87 and 90 whenever such is required.

By referring to Figures 1, 2, 3 and 4 there may be observed that part of the invention which has just been described. Figures 1, 2 and 3 show the lay 23 in its forward position at which time the follower wheel 70 is in its lowermost position and the finger 89 has its free end disposed at the front side of the lay to thus engage and draw a weft or filling thread 36a forwardly to maintain tension in the same after the shuttle has passed out of the shed of the warp yarns 57 and into the box 28 and to hold the same in this position during the return travel of the lay and as the shuttle is about to be thrown out of the shuttle box 28 to again form another weft or pick across the cloth 58.

As the lay 23 moves backwardly, or to the left in Figures 3 and 4, the follower wheel 70 will ride on the bar 66 and will be raised upwardly as shown in Figure 4. In so doing, the lower end of the finger 89 will be moved in a clockwise direction in Figure 5 and will be moved out of the path of the shuttle 35 as it is about to be thrown across the plate 26 of the lay 23. The finger 89 is curved slightly so as to clear the back of the race plate 26 when the lay 23 is at the back of its stroke to thus allow the shuttle 35 to pass by the finger 89 when it is thrown across the lay 23 by the picker stick 37. The free end of the finger 89 moves through the cut out portion 39 as the lay 23 is oscillated. The pivot point of the finger 89 as well as a depending finger 117, to be described, could be at a higher elevation, if desired, to thus avoid curving these fingers.

By referring to Figures 5, 6, 7 and 8 there may be observed a similar apparatus to that just described for performing the same function as the structure just described and it is particularly for use on the right-hand end of the lay and is a modification of that part of the invention which has heretofore been described. Either form may

be used on both ends of the lay if desired as shown in Figures 1 and 5.

Since the modified form of the invention is particularly designed for the right-hand end of a loom, only the right-hand end in Figure 5 will be described and at the other end, it being identical except opposite hand, like parts will bear like reference characters with the prime notation added.

Secured to the plate 17, by any suitable means such as a bolt 100, is a strap member 102 which extends upwardly and rearwardly and is twisted as at 103 to form a vertically disposed leaf member 104. The strap member 102' is, of course, secured by the bolt 100' to the plate 19. The leaf portion 104 has a cam-like surface 105 which is engaged by an inverted U-shaped rod 110. The rod 110 is transverse of the leaf portion 104 and has downwardly projecting portions 111 and 112 (Figures 6, 7 and 8). The portion 112 extends downwardly and is bent longitudinally of the lay to form a shaft portion 113 which is oscillatably mounted in bearings 115. The rod 110 extends through the bearings 115, as at 113, and extends downwardly and forwardly as at 117 to thus form a downwardly projecting finger portion similar to that of the downwardly projecting finger 89 at the other end of the lay heretofore described. It may be noted that the downwardly projecting finger 117 of the rod 110 passes through the slot 40 to thus engage the filling yarn as it is moved in a forward direction at its lower end.

The bearings 115, in which the rod 110 is oscillated as at 113, are secured, by any suitable means such as spot welding, to a plate 120 which has an upwardly extending portion 121 which is secured to the vertical face of the angle clip 48 by any suitable means such as a screw 122. The upwardly extending portion 121' of plate 120 at the other end of the reed cap 52 is, of course, secured to the angle clip 47 by the screw 122'. The plate 120 has a rearwardly extending portion 125 which has the upper end of a tension spring 127 secured thereto.

By referring to Figure 6 it may be observed that the downwardly projecting portion 112 of the rod 110 has secured therein a shaft 129 which extends downwardly and has a looped portion 130 to which the lower end of the tension spring 127 is secured. The spring 127 urges the rod 110 to remain in engagement with the cam surface 105 of the leaf member 104.

When the lay 23, as observed in Figure 7, is in its rearmost position the shed formed by the warp threads 57 will permit the shuttle to be thrown across the lay or race plate 26 and as the lay moves forwardly or to the left, as viewed in Figures 6 and 7, the cam surface 105 will raise the upper finger portion of the U-shaped rod 110 and will thus move the downwardly projecting portion 117 in a clockwise manner and as the shuttle leaves the shed formed by the warp yarns 57, the weft or filling yarn 36a, which is drawn through by the shuttle 35, will be picked up by the lower end of the downwardly projecting finger 117 and will take up the slack in the filling yarn 36a to thus prevent any kinking of the weft yarn 36a near the edge of the cloth 58.

It is obvious that as the lay returns from the position shown in Figure 6 to the position shown in Figure 7, the lower end of the downwardly projecting finger 117 of the rod 110 will move in a counterclockwise direction to the position shown in Figure 7 and will thus permit the shuttle to

return across the lay to start another cycle in the forming on the cloth 58.

In the drawings and specification there has been set forth a preferred embodiment of the invention, and although specific terms are employed, they are used in a generic and descriptive sense only and not for purposes of limitation, the scope of the invention being defined in the claims.

I claim:

1. In a loom having a lay with a shuttle box disposed at each end of the lay and the lay having a reed cap and a reed associated therewith, and also having a race plate, the race plate and the top of the lay on its upper face having transverse grooves disposed adjacent the ends of the reed cap, an oscillatable member disposed adjacent each end of the reed cap and having a finger projecting downwardly therefrom, fixed means on the loom adapted to engage the oscillatable member and swing its finger laterally to engage a filling cast across from one shuttle box to the other end to move the filling laterally to exert tension thereon after the filling has been extended from one shuttle box to the other and during the beat up operation.

2. In a loom having a lay and a shuttle box at each end thereof and having a reed cap and a reed therein and also having a race plate disposed on top of the lay, the shuttle boxes being adapted to receive a shuttle cast across from one end of the lay to the other, an oscillatable member mounted adjacent each end of the reed and having a downwardly projecting finger thereon and the race plate and top of the lay being cut transversely to provide a transverse groove in which the lower end of the downwardly projecting finger is adapted to oscillate, tension means for holding the finger out of the path of the shuttle and fixed cam means disposed on the loom for engaging the oscillatable means for moving the finger across the race plate and in said groove for moving a filling laterally to take up slack therein during a beat up operation, the tension means being adapted to return the finger out of the path of the shuttle when the lay moves away from beat up position.

3. In a loom having a lay provided with a race plate on the top thereof and having a transverse groove adjacent each end of the lay and a shuttle box disposed on each of the extreme ends of the lay, an oscillatable member disposed above and to one side of the top of the lay and having a downwardly projecting finger secured on one end thereof and adapted to have movement transversely of the lay in said groove, the oscillatable member having a crank portion and a fixed cam member for engaging the crank portion of the oscillatable member for moving the downwardly projecting finger transversely of the lay to engage a filling to move the filling out of a direct alignment to take up slackness therein during a beat up motion of the lay and tension means for moving the oscillatable member to cause its downwardly projecting finger to move out of the path traveled by the shuttle as the lay moves away from beat up position.

4. In a loom having a lay provided with a shuttle box at each end thereof, a pair of swords for

supporting the lay and a reed cap supported by the swords, a pair of plate members supported by the swords and having an oscillatable member mounted therein, said oscillatable member having a downwardly projecting finger fixed thereon, for movement transversely of the lay, and said oscillatable member having a crank portion thereon, tension means for normally moving the oscillatable member to a position to move the downwardly projecting finger transversely of the lay to engage a filling and move it out of a straight line for taking up slack therein, a cam member fixed on the loom and engageable with the crank portion for moving the oscillatable member against its spring tension to swing the downwardly projecting finger out of the path of the shuttle while the lay is moved away from a beat up position.

5. In a loom having a lay provided with a shuttle box at each end thereof for boxing a shuttle and having a reed through which warp threads are adapted to be passed for a weaving operation, said lay having transverse slots in its upper surface adjacent each end of the reed, an oscillatable member having a downwardly projecting finger swingable transversely of the lay in said slots and disposed at each end of the lay of the loom, tension means normally holding the finger out of the path of the travel of the shuttle, said oscillatable member having a crank arm thereon and cam means fixed on the loom for engaging the crank arm for moving the downwardly projecting finger transversely of the lay to engage a filling during a beat up operation to move the filling out of a straight line to remove any slack therein during a beat up operation.

6. In a loom having a lay provided with a race plate on the top thereof and having a transverse groove adjacent each end of the lay and a shuttle box disposed on each end of the lay, an oscillatable member disposed above and to one side of the top of the lay and having a downwardly projecting finger on one end thereof and adapted to have movement transversely of the lay in said groove, the oscillatable member having a crank portion, a fixed cam member for engaging the crank portion of the oscillatable member, tension means secured to the crank portion and a portion of the lay for moving the finger transversely of the line of travel of the shuttle when the lay oscillates in one direction and the cam member engaging the crank portion for moving the finger in the opposite direction relative to the lay when the lay oscillates in the other direction.
